[57] CLAIM

The ornamental design for a clamp for safety harness, as shown and described.

DESCRIPTION

FIG. 1 is a perspective view of a clamp for a safety harness showing my new design;

FIG. 2 is a left side elevational view thereof;

FIG. 3 is a right side elevational view thereof;

FIG. 4 is a rear elevational view thereof; and,

FIG. 5 is a bottom plan view thereof.

The broken lines showing of a plank in FIGS. 1-3 is for illustrative purposes only and forms no part of the claimed design.
